UNITED STATES PATENT OFFICE

ELTON D. KOHR, OF YORK, PENNSYLVANIA, ASSIGNOR TO KOHR'S CUSTARD STORES, INC., OF YORK, PENNSYLVANIA, A CORPORATION OF DELAWARE

DESIGN FOR A FROZEN-PRODUCT MACHINE FRONT

Application filed June 18, 1930. Serial No. 36,077. Term of patent 14 years.

To all whom it may concern:

Be it known that I, ELTON D. KOHR, a citizen of the United States, residing at York, in the county of York and State of Pennsylvania, have invented a new, original, and ornamental Design for a Frozen-Product Machine Front, of which the following is a specification, reference being had to the accompanying drawing, forming a part hereof.

The figure is a perspective view looking

towards the outer side of a frozen-product machine front, showing my new design. The rear side, not shown of the front is formed adjacent its edge with a forwardly directed annular recess having its base provided with an axial opening.

What I claim is:

The ornamental design for a frozen-product machine front, as shown and described.

ELTON D. KOHR.
